MACHINE FOR USE IN THE BENDING OF
EDGES OF METAL SHEETS INTO BEAD
FORMWilliam Harold Harvey and Percy Ronald
Harvey, Wellington, New ZealandApplication June 9, 1932, Serial No. 616,349
In New Zealand September 23, 1931

1 Claim. (Cl. 153—46)

This invention has been devised primarily for use in the manufacture of house spouting or guttering of the desired forms from metal sheets, and in which a rounded bead is formed on the outer edge for the purposes of strengthening the formation and in some cases also to provide for the clipping of the spouting within the supporting brackets. The machine is devised with the object of providing simple, cheap and efficient means whereby this bead may be formed on the sheet edge as the first operation in the shaping of the sheet into its usual spouting form.

The machine is, however, suitable for use in all other circumstances in which it is desired to bend a metal sheet edge into a roll or bead of rounded or circular nature.

The invention comprises the provision of a former or mandrel plate member of approved length that is shaped with a deep narrow cut or groove extending parallel with its outer edge at a distance in therefrom, and that at its edge is rounded into approximately circular form in cross section. The edge of the metal sheet to be bent into the beaded form is inserted in such cut or groove and the sheet then bent round the rounded edge. For this purpose the invention also comprises the combination with such mandrel member of means whereby the metal sheet for its full length may be wrapped round the rounded edge in an even and quick manner. These means preferably are of a nature such as to turn the sheet upon a stationary mandrel, but they may provide for the mandrel turning with the sheet to engage a fixed face and bend the sheet edge round the mandrel's edge.

In fully describing the invention reference will be made to the accompanying sheet of drawing, in which:—

Figure 1 is a sectional sketch illustrating the principle concerned with the formation of the mandrel member and the shaping of the bead thereon.

Figure 2 is an end elevation of the bead as shaped in the mandrel shown in Figure 1.

Figure 3 is a cross sectional elevation, and

Figure 4 a plan, of a suitable form of machine for giving effect to the invention and embodying a stationary mandrel.

In giving effect to the invention a horizontal metal plate A, which conveniently forms part of a table, has a deep and narrow groove B cut in its top surface for its full length, that is parallel with the outer edge of the plate at a distance in from such edge, and then has the portion outside such groove rounded into approximately

circular form in cross section, as shown clearly in Figure 1 to form a mandrel C. When therefore a metal sheet D has its edge inserted into the groove and is bent across from the inside to the outside and round upon the outside of the mandrel C, such edge will be bent into conformity with the cross sectional shape of the mandrel as indicated by the dotted lines in Figure 1, and the full lines in Figure 2. The formed sheet may then be removed from the mandrel by sliding it longitudinally along and off one end thereof.

In the form of the invention shown in Figures 3 and 4 the said plate A, which is of any approved length suitable for the length of sheets to be operated upon, is made double edged to provide an upwardly projecting mandrel C along each edge. This is adapted to be fixed, with either edge on the outside, by bolting it to a bracket bar E that is fixed upon the table F so that the mandrel plate A extends out clear of such table. These mandrel edges C may be of different sizes, as shown, to adapt the machine for the formation of beads of two different diameters. Also the groove B within the mandrel edge C on each edge is formed by the combination with the mandrel plate, of an upper plate G that fits in between the rounded edges C and is fastened to the plate A by means of stud bolts H passing through it and into the plate A. Each of these stud bolts passes through a short transverse slot J formed in the plate G so that the plate may be moved transversely to vary the width of the groove B along either edge, and thus to adapt it for the neat fitting of varying thicknesses of metal sheets within the groove.

This plate A may however be made single edged and be fitted to form the top edge corner of a table surface, as in Figure 1.

Combined with the mandrel plate are means for bending the metal sheet round the mandrel when such sheet has had its edge inserted in the groove B to be held therein. These means comprise a round bar K that is made of about the length of the plate A and is supported to extend parallel with such plate by attaching its two ends respectively to the outer ends of levers M that are pivoted at their inner ends to bearings N formed upon or attached to the respectively corresponding ends of the bracket bar E. By reason of this arrangement the bar, while maintaining its parallel relationship with the mandrel plate A, may move in an arc out from behind the plate, across its top, and then down over its front edge as indicated by the series of dotted circles in Figure 3. Its axis of turning and its position on the

levers M, are so arranged in relation to the plate A, that as the bar moves down to pass across the front edge of the plate it approaches closely to such edge and then follows round the contour of the mandrel's surface. For turning the bar in this manner it is provided with handle levers O affixed to it, one near each end, which extend in lines radial with the pivot axes of the levers M. If desired, the bar K may be made adjustable in its mounting upon the levers M by forming each lever with a longitudinal slot and attaching the bar end to it by a bolt pin P projecting from such end and passing through such slot. This arrangement also will permit of the bar being adjusted to a uniform parallel relationship with the mandrel.

It will thus be seen that if the bar K is turned back upon the table F and the metal sheet D arranged with its edge in the groove B of the mandrel, the turning up and over of the bar will cause it to engage the sheet and carry such sheet with it so that the sheet edge is wrapped round upon the mandrel, to shape it correspondingly. Different forms of beads may thus be made, the form shown in Figure 2 being obtained by first bending the sheet in any of the known machines for this purpose, to form a right angled bend at a distance from the edge to be beaded. The bent sheet is then arranged in the machine as shown in Figures 1 and 3 by placing the bent

edge vertically in the groove, with the main portion extending horizontally rearward above the bar K. During the wrapping of the sheet edge round the mandrel the edge will be retained in the groove by reason of its narrow nature and the frictional grip exerted on it by the groove faces, brought about by the lateral pressure of the bar on its main portion.

We claim:

Means for the formation of beads upon the edges of metal sheets, comprising in combination a fixed metal support having both of its marginal edges enlarged and rounded, an elongated mandrel plate mounted for lateral shifting movement on the upper surface of the support and of a width less than the enlarged rounded edges thereof, means for releasably clamping the mandrel plate on the support so as to provide various width grooves between it and the rounded edges, a pair of lever arms pivoted one at each end of the support so as to swing transversely of the support and each having a slot extending along its length, a round bar arranged to extend between the lever arms and adjustably attached at each of its ends to the corresponding lever by fastening within the slot itself, and handle bars affixed to radiate from said round bar and extending in the same radial lines as the lever arms.

WILLIAM HAROLD HARVEY.
